TIME ELEMENT.

1,176,634.

Specification of Letters Patent. Patented Mar. 21, 1916.

Application filed May 12, 1914. Serial No. 838,123.

To all whom it may concern:

Be it known that I, ALBERT AICHELE, a citizen of the Swiss Republic, and residing at Baden, Switzerland, have invented certain new and useful Improvements in and Relating to Time Elements, of which the following is a specification.

This invention relates to time element mechanism for overload contacts and the like.

Time elements have already been proposed in which the clockwork is driven by an electric motor. In these the rotor of the clockwork motor is arranged in the iron circuit of the relay magnet itself, so that the relay magnet supplies the field in which the rotor rotates. The clockwork after the expiration of a certain adjustable time limit unlocks the locking means for the lever effecting the cutting out of the excessive current, whereby also current is cut off from the magnet winding of the time element and the relay resumes its initial position.

The object of the present invention is to provide an improved construction of this kind.

The invention consists in a time element mechanism driven by an electric motor or otherwise the rotor being arranged in the iron circuit of an electro-magnet with movable armature, the arrangement being such that on the maximum permissible current being exceeded one end of the armature is first attracted whereby the driving mechanism of the clockwork is geared up, the other end of the armature remaining locked until the clockwork has run down, this end of the armature only being attracted after the release of the locking means to cause, for example, the opening of the main switch.

The invention also consists in an arrangement of this kind with means whereby a short-circuit or other heavy overload causes both ends of the armature to be attracted.

In the accompanying diagrammatic drawings:—Figure 1 shows the position of the parts when a normal current is flowing; Fig. 2 shows their position just after a current above the maximum permitted has begun to flow; Fig. 3 shows the position which the parts take for instance after the aforesaid

excess current has flowed for a predetermined time.

Some of the inductors illustrated in Fig. 1 are omitted from Figs. 2 and 3. The shafts which are shown with section lines are intended to be fixed in space.

In Fig. 1 the electro-magnet *a* is provided with a winding *b* through which the current flows and a limb *r* containing the rotor *c* of an electromotor operated on the shaded pole principle. This motor drives the gear wheel *l* which by means of the pinion *2* drives the wheel *n* mounted on the spindle *d*. On this spindle is also mounted the pinion *3* and pivoted the arm *e* connected to the main switch or the like by a rod *3*. To the arm *e* is pivoted at the point *h* an armature *f*; this at one end is formed with a curved pole piece *g* and at the other end *k* has a wheel *l* pivoted to it and also connected to it by means of the springs *s* and the screw *t*. The armature *f* also carries a flat spring *4* bearing on the rotor *c* and a connection for a spring *i*, the tension of which can be varied by apparatus *5*. The plate *l* has a projection *m* of sufficient length to engage a locking bar *o* with a notch *6* in which a projection *7* on the bar *e* normally engages. The plate *l* is provided with a slot *u* so that it can move on the spindle *n* and is controlled by the spring *p* which can be tensioned by apparatus *8*.

In operation the springs *i*, *p* and *s* are first suitably tensioned until the various indicators show the ordinary maximum permissible current, the short-circuit current and the time element being allowed. With excessive current the magnet *a* attracts the end *k* of the armature *f*, thus overcoming the action of the spring *i*, so that the said end turns about *h*. By this means the teeth provided on the disk *l* are in the first place caused to engage with the gear wheel *m* of the motor *c* and further the plate spring *4*, which up to that moment prevented the rotor *c* from rotation is lifted out of contact with the said rotor. This position of the apparatus is shown in Fig. 2. The rotor *c* now at once starts to rotate and to drive the disk *l* in the direction indicated by the arrow against the action of the spring *s*. After a few seconds the projection *m* then strikes against the locking lever

o, thus forcing the same in an upward direction, so that it is unlocked at q. The magnet a now immediately attracts the other end g of the armature f causing the release lever 5 e to share in its movement and to open the main switch or the like (not shown). The parts now assume the position shown in Fig. 3 but only for a moment.

Immediately after the attraction of the 10 armature, the coupling between the disk l and the train of wheels n is disconnected as shown in Fig. 3, so that the disk l is rapidly turned by the spring s into its initial position (Fig. 1), that is to say, until the pin t 15 comes into contact with the armature f. The armature f also only remains for a short moment in the closed position as on release of the main switch, the winding b is rendered currentless and the relay magnet releases its 20 armature, so that it returns in the position shown in Fig. 1.

On short-circuiting the time element is cut out because in consequence of the increased 25 tractive effort of the relay magnet a, the armature f may be attracted at both ends k and g without unlocking q, the necessary motion of the locking bar o being permitted by the slot u.

If now in consequence of a short-circuiting 30 of the tractive effort of the magnet has increased to such an extent that it overcomes the force of the spring p then the projection q on the lever f pushes back the locking lever o, causing v to slide in the slot u and the release is effected instantaneously.

The current intensity for the time release 35 may be adjusted by the tension of the spring f and the current intensity for the short-circuit release by the tension of the spring p. The time interval between responding and 40 release may be regulated by shifting the pin t on the disk l.

As the speed of the motor c depends upon 45 the periodicity and not upon the current intensity in the winding b, the time between the responding and release of the relay is also independent of the releasing current. A clockwork motor, however, might be used, the speed of which would be dependent in 50 some manner upon the releasing current. The releasing period would then be dependent upon the releasing current.

Arrangements as described above have the 55 advantage that the armature does not "stick" but is immediately released when the exciting current of the relay falls to its permissible value even before the running down of the clockwork. The reason of this is the iron circuit of the relay magnet comprises 60 two air gaps, so that when the magnet has attracted one end of the armature, there still remains an air gap which, as is well known, prevents an excessive increase of the field, and consequently a "sticking" of the arma-

ture. This effect is further increased by the 65 circumstance that the path which must be traversed by the armature in order to couple the clockwork to its driving member, and consequently the distance separating the respective end of the armature from the relay 70 magnet need only be very small, whereas mostly a shorter path must be traversed by the armature for the purpose of effecting a release. The air gap which is bridged in the first place owing to the one-sided attraction 75 of the armature on the occurrence of an excessive current, amounts therefore only to a small fraction of the total air gap at both ends of the armature.

Having now described my invention what 80 I claim as new and desire to secure by Letters Patent is:—

1. Time element mechanism comprising an electro-magnet, a lever with a projection thereon, an electro-magnet armature pivoted 85 on the lever, a toothed disk carried on said armature, gearing adapted to drive said toothed disk and a motor arranged to drive said gearing, a locking lever with a notch engaging the projection on the first mentioned lever and springs controlling the action respectively of the electro-magnet armature, the toothed disk and the locking lever.

2. Time element mechanism comprising an 90 electro-magnet, a rotor disposed in a gap in said magnet and adapted to be driven thereby, a train of gearing in connection with said rotor, a pivoted lever with a projection, an armature for said electro-magnet pivoted 95 on said lever, a toothed disk having a projection and also a slot, said disk being mounted on said electro-magnet armature, a blade spring connected with said armature and adapted to press on said rotor, a locking 100 lever having a notch to engage the projection on the first mentioned lever and a slot to permit motion of said lever, together with a projection arranged in the path of the projection on the toothed disk, a spring 105 connecting the electro-magnet armature to the toothed disk by way of the slot therein, a further spring in connection with said armature and a spring in connection with said locking lever with means for adjusting the 110 tension of said springs.

3. Time element mechanism comprising an 115 electro-magnet, a pivoted lever, an armature for said electro-magnet pivoted to said lever near one of the poles of the electro-magnet and so disposed that the gap at this pole shall be greater than the gap at the other pole, gearing and means for driving the 120 same, and a toothed disk mounted on the electro-magnet armature so as to be driven 125 by said gearing.

4. Time element mechanism comprising an electromagnet with two gaps, a pivoted

lever acting as an armature and arranged in proximity to one gap, a train of gearing, one gear wheel of said train being mounted on the aforesaid armature; a rotor disposed in the second gap and forming with said electromagnet an electric motor, means connecting said rotor to said train of gearing for the motor to drive the aforesaid train, a switch and means for operating same after

the aforesaid train of gearing has been 10 driven to a predetermined extent.

In testimony whereof, I affix my signature in presence of two witnesses.

ALBERT AIGHELE.
